INVENTOR.

UNITED STATES PATENT OFFICE.

THOMAS C. SPELLING, OF NEW YORK, N. Y.

COMBINATION OF CLOSURES AND PULLERS FOR BOTTLES AND OTHER CONTAINERS.

1,377,527.

Specification of Letters Patent.

Patented May 10, 1921.

Application filed August 10, 1918. Serial No. 249,312.

To all whom it may concern:

Be it known that I, THOMAS C. SPELLING, a citizen of the United States, residing at New York city, in the county of New York 5 and State of New York, have invented certain new and useful Improvements in Combinations of Closures and Pullers for Bottles and other Containers, of which the following is a specification.

10 This invention relates to closures for bottles and combinations thereof with pullers, and has for a purpose the provision of a lock connected with a binder for the stopper adjustable by a simple act of revolving a cap, 15 or plate, and of a puller insertible in the stopper which also serves to bind the cap, or plate, thereon, the mechanism being such that the stopper, puller and binder are combined and removable without disengagement, dismemberment or separation, the one 20 from the other.

Perhaps it is not least important that provision is here made, by constructing an underlying segment and a cam face shoulder 25 on the rim, for the use of machinery for emplacement. The ordinary bottle rim cannot withstand the force that must be exerted by a machine in motion for bending the parts and forcing other parts into locked 30 relation. And I provide a locking plate and arms specially adapted for use with that construction.

Figure 1 is a top view of a bottle having its stopper secured by my improved device. 35 Fig. 2 is a section on the line 2—2 of Fig. 1, with the plate (11) intact. Fig. 3 is a side elevation looking in the direction of the arrow A in Fig. 1. Fig. 4 is a diametrical section of the bottle neck and cork, with the 40 puller intact.

Referring to the drawing by reference numerals, 4 designates a jar or a bottle whose neck 5 is formed with an enlarged rim 6 having two segmental projections, 6^a, 45 each of which is formed with a shoulder 7 and, adjacent thereto, with a cam face 8 having a notch 9.

Upon the stopper 10 is placed a plate 11, having two downwardly bent arms 12 formed with projections 13, each of which is 50 provided with a tooth 14 and an aperture 15, the use of which will presently be described.

The plate 11 is provided with a central aperture 16 and slots, 17; and beyond the 55 ends of the slots are acute downward bends, 18, the purpose being to utilize resiliency and facilitate the act of locking. The stopper extracting device consists of the prong 19 having a bar 20 and ring 21. Said extracting device being fully described in my U. S. application above referred to, I need not here describe it but will only describe its use in combination with the plate 11, 60 which use is as follows:

The plate 11 is placed centrally upon the stopper, and so positioned that the slots, 17, are in alinement with the notches, 9, in the shoulders, 7, and the extractor is then forced down through the slots 17 and into the 70 stopper until the bar 20 reaches the upper surface of the stopper, 10, or if necessary, in order to obtain perfect adjustment, the lower edge of the bar may be pressed down into the top of the stopper and into the cut 75 made by the descending extractor. This is done while the arms 12 are in the position shown in dotted line in Fig. 1. The ring 21 is then given a preliminary pull so as to spread the wings 19^a of the prong to the inclined positions shown in Fig. 3, this movement bringing the bar 20 above the plate 11. The plate 11 is then turned until the arms 80 12 stop against the shoulders 7 and the teeth 14 snap into the notches, 9. This leaves the 85 plate locked against accidental rotation while by combined action of the parts, the stopper is firmly held down and locked in place.

When the stopper is to be extracted, the 90 projections 13 are disengaged by any suitable tool inserted in the aperture, 15. The plate is then rotated sufficiently to cause the projections, 13, to fully clear the shoulders 7. An upward pull at the ring 21 will then 95 extract the stopper.

The puller described in said application has smooth and practicable coaction with this locking device. Alone it is effective to extract the stopper without external mutilation. In this combination, it is inserted through the slots, 17, adjacent to the central aperture, 16, while the plate and arms thereof are alined at right angles to their final 100 positions. In Fig. 4 is shown how the preliminary pull raises the puller from the dot- 105

- ted position, 24, to the full line position 26, and thereby causes the inclined points, 23, of the wings, 19^x, to spread said wings from the dotted position, 22, to the full line position, 26, by which they are firmly engaged in the stopper to pull it. Obviously, an incidental result of the pull is to move the point, 25, upward, corresponding with the upward movement of bar 20 and ring 21.
- 10 In order to set the wings, 19^x, as shown in Fig. 3, a preliminary pull at the ring, 21, and a slight movement upward of the prong, 19, is required. That raises the bar, 20, above the plate, 11, which is now turned 15 half around into locked relation. The ring, 21, being now released, resilient reaction occurs and bar, 20, comes to rest with resilient pressure on the plate, across aperture, 16, as seen in Fig. 2.
- 20 It is obvious that variations in the forms of construction would be feasible without departing from the principle or general plan of the invention; and, therefore, I do not, by the foregoing specification, or the 25 illustrations or by these claims, intend placing a limitation upon the adoption of new forms of construction in keeping with said principle and plan.

Having now fully described the invention, 30 I claim as follows:

1. The combination of a locking closure for a bottle with a bottle, the bottle formed with segmental projections of the rim around the mouth, each segmental projection formed with a shoulder and, adjacent thereto, a cam face, the latter notched for engagement with a tooth on a projection of an arm of a locking device.
2. The combination of a bottle with a 40 locking closure, the locking closure comprising a stopper equipped with a puller anchored therein and a locking plate attached to the stopper, the locking plate formed with an aperture and slots at the center for engagement of the plate with and under the horizontally positioned bar of the puller in place, having also beyond and alined with the slots downward bent arms, and on the arms lateral projections on which are 45 formed teeth for engagement, in locked relation, with notches formed in cam faces of shoulders of outer segments of the rim around the mouth of the bottle.
3. In a combination, as described, the sub- 55 combination of a puller for a stopper with a revoluble locking plate, the puller formed of resilient material and consisting of a prong sharply pointed at one end, having also sharpened exterior edges adjacent to the point, wings on laterally extended portions of the prong, each wing bluntly shoul- 60 dered on each side of a sharp point formed centrally thereon and slanted at an angle from the plane of the wing, each wing slant-

ed at an angle from the plane of the prong, 65 and a centrally apertured bar at the end opposite the pointed end, the plate formed with downwardly bent arms and rectangularly disposed projections thereon, the plate also centrally apertured and slotted on each 70 side of the aperture, the slots in right angled relation to the greater width of the apertured bar of the puller, in place, the projections on the arms formed with teeth for engagement in notches in the rim of a 75 bottle.

4. In a combination, as described, the sub-combination of a puller for a stopper with a revoluble locking plate, the puller formed of resilient material and consisting of a 80 prong sharply pointed at one end, having also sharpened exterior edges adjacent to the point, wings on laterally extended portions of the prong, each wing bluntly shoul- 85 dered on each side of a sharp point formed centrally thereon and slanted at an angle from the plane of the wing, each wing slanted at an angle from the plane of the prong, and a centrally apertured bar at the end opposite the pointed end, the plate formed 90 with downwardly bent arms and rectangularly disposed projections thereon, the plate also centrally apertured and slotted on each side of the aperture, the slots in right angled relation to the greater width of the 95 apertured bar of the puller, in place, the projections on the arms formed with teeth for engagement in notches in the rim of a bottle, the tooth on each projection positioned on the interior edge of the projec- 100 tion and at the junction of a horizontal and a slanted section of the edge.

5. In a combination, as described, a bottle formed with segmental projections in the rim around the mouth, each of which is 105 formed with a shoulder and, adjacent thereto, a cam face, the latter notched for engagement with a tooth on a projection of the arm of a locking device.

6. In a combination as described, a device 110 for locking a stopper in the mouth of a bottle, formed of metallic plate with an aperture and slots at the center for engagement of the plate with and under the horizontally positioned bar of a puller, having 115 also beyond and alined with the slots downward bent arms and on the arms lateral projections on which are formed teeth for engagement, in locked relation with notches formed in cam faces of the shoulders of 120 outer segments of the rim around the mouth of the bottle.

7. In a combination as described, a device 125 for locking a stopper in the mouth of a bottle, formed of metallic plate with an aperture and slots at the center for engagement of the plate with and under the horizontally positioned bar of a puller, having

also beyond and alined with the slots downward bent arms and on the arms lateral projections on which are formed teeth for engagement, in locked relation with notches 5 formed in cam faces of the shoulders of outer segments of the rim around the mouth of the bottle, the tooth on each projection positioned on the interior edge of the pro-

jection and at the junction of a horizontal and a slanted section of the edge. 10

In witness whereof I affix my signature in presence of two witnesses.

THOMAS C. SPELLING.
